PAGE 2

Fig. 2

Fig. 3

Fig. 4

I claim:

The ornamental design for a basin for a baby bath, substantially as shown and described.
